(57) **CLAIM**

The ornamental design for a projectile launcher, as shown and described.

DESCRIPTION

FIG. 1 is an isometric view of a first embodiment of the projectile launcher;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is another isometric view thereof;

FIG. 9 is an isometric view of a second embodiment of the projectile launcher;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof;

FIG. 16 is another isometric view thereof;

FIG. 17 is an isometric view of a third embodiment of the projectile launcher;

FIG. 18 is a front view thereof;

FIG. 19 is a rear view thereof;

FIG. 20 is a right side view thereof;

FIG. 21 is a left side view thereof;

FIG. 22 is a top view thereof;

FIG. 23 is a bottom view thereof; and,

FIG. 24 is another isometric view thereof.

The evenly spaced dashed lines in the Figures depict portions of the projectile launcher that form no part of the claimed design.

(Continued)

The dot dash lines represent a boundary of the claimed design and form no part of the claimed design.
